UNITED STATES PATENT OFFICE.

HENRY WILLIAM ILLENBERGER, OF NEW ORLEANS, LOUISIANA.

ANTIRATTLER AND SASH-ADJUSTER FOR WINDOWS.

1,105,438.

Specification of Letters Patent. Patented July 28, 1914.

Application filed April 1, 1914. Serial No. 828,730.

To all whom it may concern:

Be it known that I, HENRY W. ILLENBERGER, a citizen of the United States, and a resident of New Orleans, in the parish of Orleans and State of Louisiana, have invented a new and Improved Antirattler and Sash-Adjuster for Windows, of which the following is a full, clear, and exact description.

10 This invention relates to an improved anti-rattler for windows and the object of the invention is to provide a simple and novel device which will also possess the capabilities of operating to hold a sash in an 15 adjusted position when raised or lowered, in addition to preventing the sashes from rattling and causing the same to fit tightly in the guideways of the frame in such a manner as to exclude draft and wind and the 20 effects of inclement weather.

With the above and other objects in view, the invention resides in the peculiar combination and arrangement of parts to be hereinafter more fully described, illustrated 25 and claimed, it being also an object to provide a device which is simple in construction, durable and efficient in operation and not likely to get out of working order.

Reference is to be had to the accompanying drawings forming a part of this specification, in which similar characters of reference indicate corresponding parts in all the views, and in which—

Figure 1 is a fragmentary elevation of a 30 window frame with sashes mounted therein illustrating the application of the improved anti-rattler and sash adjuster; Fig. 2 is an enlarged sectional view taken on the line 2—2 of Fig. 1 and looking in the direction 35 indicated by the arrows; Fig. 3 is an enlarged sectional view of the improvement; and Fig. 4 is an end elevation of the device looking upwardly with relation to Fig. 3.

As illustrated, the improved anti-rattler 40 and sash adjuster comprises an inner tube or shell 10 having a closed end wall 11 preferably slightly rounded or convex as shown, and provided at its opposite open end with an outwardly directed flange or retaining 45 part 12. This tube or shell is fitted within an outer tube or shell 13 having an inturned flange or engaging part 14 at one end and having its opposite end formed with a plurality of bendable projections 15 providing 50 means to partially close the end of the tube after the shell 10 has been fitted in the shell

13 to cause the convex or rounded end to protrude through the flanged end thereof, and an expansible coiled spring 16 is fitted inside the tubes or shells between said convex wall 60 and said projections. These projections are bent inwardly in the manner shown in Figs. 3 and 4 so that the spring normally holds the tube or shell 10 constituting one of the pairs of telescopic sections forming the 65 device distended relative to the other tube or section.

In the application of the invention to a window, a portion of which is indicated by the numeral 17 in Figs. 1 and 2 of the drawings, the sashes 18 are drilled with holes or sockets 19 in the outer face of the sash frame within the area of the parting strips 20. These sockets are preferably located two at each side of the sash and near the top and 75 bottom edges thereof, and the devices are fitted therein by telescoping the shells or sections against the action of the springs 16 in the manner shown in Fig. 2 of the drawings so as to cause the convex ends of the 80 shells or sections 10 to contact with the parting or other guide strips of the frame. In this manner the sashes will be tightly held in position by contacting with the opposite 85 guide strips and when the sashes are raised 90 or lowered they may be held in any particular adjusted positions by reason of the frictional contact of the sashes with the guide strips and of the parts 10 with the other guide strips.

The device is particularly adapted for sashes weighing eight pounds or less, wherein a series of minute springs applied as specified can hold the sashes from binding 95 in the frame and permit the raising and lowering thereof in the usual way without the necessity of employing weights, pulleys and sash cords. Tight joints will also be formed between the sashes and the frames so as to exclude wind and cold or rain and 100 like effects of inclement weather. A great deal of convenience will also be derived due to the relief from the annoyance of rattling windows and the obvious disadvantages and objections thereto, especially by sick and 105 nervous people. The tubes or shells are preferably constructed of brass while the springs are preferably made of spring steel.

Having thus described my invention, what I claim as new and desire to secure by Letters Patent is:—

1. An anti-rattler and sash adjuster for

- windows, comprising an inner tube having a rounded end wall and an out-turned flange at its other end, an outer tube having an in-turned flange at one end to be contacted by
5 the out-turned flange of the first-mentioned tube to limit the distension of the inner tube and the outer tube, a coiled spring mounted within the tubes, and a series of projections formed at the opposite end of the outer tube
10 to retain said spring from displacement and cause the same to normally distend the inner tube, as and for the purpose described.
2. An anti-rattler and sash adjuster for windows, comprising an inner tube having
15 a closed end wall and an integral outwardly extending flange at its opposite end, an outer and larger tube having an integral inturned flange at one end, said inner tube being adapted to be fitted into the outer tube
20 whereby its closed end will project through the flanged end of the outer tube to dispose

the two flanges for engagement to limit the projection of the inner tube with relation to the outer tube, a spring within the tubes tending to normally hold the tubes in the 25 last-named position, means formed at the opposite end of the outer tube and bent over after the application of the spring to form an engaging member for the latter and prevent displacement thereof, said inner tube 30 at its flanged end being adapted to engage said last-named means to limit the inward movement of the inner tube with relation to the outer tube and the compression of the spring.

In testimony whereof I have signed my name to this specification in the presence of two subscribing witnesses.

HENRY WILLIAM ILLENBERGER.
